T. FAIRBANK.
PLATFORM SCALE.

No. 25,962.

Patented Nov. 1, 1859.

UNITED STATES PATENT OFFICE.

T. FAIRBANKS, OF ST. JOHNSBURY, VERMONT.

PLATFORM-SCALE FOR RAILROADS, &c.

Specification of Letters Patent No. 25,962, dated November 1, 1859.

To all whom it may concern:

Be it known that I, THADDEUS FAIRBANKS, of St. Johnsbury, in the county of Caledonia and State of Vermont, have invented 5 a new and useful Improvement in Platform-Scales for Weighing Heavy Bodies; and I do hereby declare that the same is fully described and represented in the following specification and the accompanying drawings, of which—

Figure 1, is a top view of a railroad platform scale without the upper planking of the platform the same being to exhibit the coupling levers and their supports. Fig. 15 2, is a longitudinal and vertical section of the coupling apparatus and its pit. Fig. 3, is a transverse section, taken through the middle of the platform. Fig. 4, is a transverse section of the platform and pit masonry, while Fig. 5, is an end view of the 20 same. Figs. 6 and 7, are top and side views of one of the longitudinal timbers of the platform.

My invention or improvement is particularly intended for what are termed railway platform scales or such as are employed in the track of a railroad, and for weighing the carriages or trains thereof.

The nature of my invention consists in an 30 arrangement of the supporting standards and the loops or supports of the longitudinal levers and platform with respect to each other and so as to extend within or into the space between the side timbers of 35 the platform, the said arrangement being productive of several important advantages as respects construction and operation of the weighing apparatus.

In the drawings, A, exhibits the platform 40 for supporting the cars or bodies to be weighed, the same being constructed of two parallel, longitudinal timbers *a*, *a*, united by transverse planks *b*, *b*, and by sundry cross ties, *c*. Within the space, *d*, between 45 the timbers, *a*, *a*, I arrange a series of longitudinal weighing levers, *B*, *B*; *C*, *C*. Each of the outermost of which (or those marked, *B*, *B*) is composed of a cross shaft, *e*, and five arms, *f*, *g*, *g*, *h*, *h*, projecting therefrom 50 as shown in the drawings. Each of the other levers, or those marked, *C*, *C*, is composed of a similar shaft, *i*, and six arms *l*, *m*, *m*; and, *n*, *n*, arranged as shown in 55 the drawings. The two inner arms of the levers, *C*, *C*, being suspended at their inner ends from a transverse

weighing lever, *D*, arranged as shown in Figs. 1, and 3. Furthermore, within the pit, and resting on its bottom, or made to project upward therefrom, a timber frame, *E*, is disposed; in the pit, as shown in the figures, is a series of standards, *F*, *F*, each of which has two posts, *o*, *o*, on whose tops, a round cross bar or bridge is supported. The several standards, *F*, *F*, extend upward into the space between the side timbers of the platform, there being one of such standards to each pair of the shorter arms of the longitudinal levers.— Each pair of such shorter arms is suspended 60 from the cross bar of its standard by means of a loop, *r*, placed between the two arms of the pair, and having a knife edge bearing, *s*, extending through it and fixed in 65 the arms. 70

Immediately under the two sets of shorter arms of each longitudinal lever there is a metallic cross bar, *t*, or the equivalent thereof, it being attached at its ends to the two longitudinal timbers of the platform or 75 made to extend from one to the other. This bar, *t*, rests in a loop, *u*, placed immediately under each pair of the shorter arms of the adjacent lever such loop being suspended from *a*. Knife edge bearing, *v*, supported 80 between and by such pair of arms.

From the above, it will be seen that the platform is supported by the levers by means of the bars, *t*, and their suspension loops, while the levers are supported by the 85 standards by means of suspension loops, all of such loops being arranged so as to enable the longitudinal weighing levers to have a swinging movement lengthwise of the platform.

By means of stay rods *w*, *w*, *x*, *x*, arranged as shown in the drawings, the platform is prevented from having a swinging movement and is only movable in vertical 90 directions. Each two longitudinal levers 100 *B*, *C*, are connected by a loop, 2.

The advantages of my arrangement over that when the platform rests on the levers, are, that the levers are relieved from, or are not liable to being bound or cramped 105 as they are when the platform rests directly on them. Furthermore the bearings of the platform being of the character described, and arranged so as to swing longitudinally are enabled with the levers to be arranged 110 in the space between the longitudinal timbers of the platform. This diminishes the

depth of the pit or renders a very shallow pit necessary relatively to what would be required were transverse levers used in connection with the longitudinal levers, and 5 arranged under the platform timbers as seen in my Patent No. 445, of reissues of United States patents.

By extending the standards up between the longitudinal timbers instead of outside 10 of them, we can diminish the width of the pit comparatively and thus effect a saving in cost. Furthermore, the whole system of levers, is free to vibrate, or has a freedom of action which causes the bearing parts

thereof to always assume the proper positions for weighing correctly. 15

I claim—

The arrangement of the supporting standards and the loops or supports of the longitudinal levers and platform with respect 20 to each other and so as to extend within or into the space between the side timbers of the platform substantially as specified.

THADDEUS FAIRBANKS.
